ALTAR OR THE LIKE

Bernard J. Tanning, Grand Rapids, Mich., assignor to American Seating Company, Grand Rapids, Mich., a corporation of New Jersey

Filed Mar. 20, 1959, Ser. No. 55,068

Term of patent 14 years

(Cl. D29—23)

Figure 2 is a front elevational view thereof;
of the altar, taken on line 4—4 of Figure 3.
The rear of the altar is of open, conventional configuration.

I claim:

The ornamental design for an altar or the like, substantially as shown and described.
